UNITED STATES PATENT OFFICE.

WEBSTER LOKEN, OF WINDOM, MINNESOTA.

ATTRITION MILL.

Application filed October 30, 1926. Serial No. 145,203.

My invention relates to attrition mills and more particularly to a feeder for producing a constant uniform flow of stock to the grinding plates of a mill.

5 Feeding devices heretofore used have not been entirely satisfactory for the reason that they choke up and clog and thereby produce an uneven stock to the grinding plates which causes an overload on the motors that drive 10 said plates, part of the time and an under-load the balance of the time, thus making it expensive to operate an attrition mill.

It is customary to provide attrition mills with reversible motors for independently 15 operating the grinding plates so that when the ribs on said plates are worn off on one of their edges said motors may be reversed to drive said plates in opposite directions until the other edges of their ribs are worn 20 off, thus doubling the life of said plates.

By the use of my improved feeder a constant uniform flow of stock is delivered to the grinding plates so that there is a constant uniform load on the motors. The invention further provides means for operating 25 the feeder from one of the motors of the mill in a given direction, irrespective of the direction of rotation of the grinding plate operated by the respective motor.

30 To the above end, generally stated, the invention consists of the novel devices and combinations of devices hereinafter described and defined in the claims.

In the accompanying drawings, which 35 illustrate the invention, like characters indicate like parts throughout the several views.

Referring to the drawings:

Fig. 1 is a side elevation of an attrition 40 mill having the invention embodied therein, with some parts broken away and other parts shown in central vertical section;

Fig. 2 is a plan view of the same with some parts sectioned on the line 2—2 of Fig. 45 1; and

Fig. 3 is a detail view in section taken on the line 3—3 of Fig. 2, on an enlarged scale.

The attrition mill illustrated includes a bed 4 on which is mounted a pair of electric 50 motors 5 of the reversible type, the armature shafts 6 of which are axially spaced and axially aligned. Said armature shafts 6 are mounted in bearings 7 on the bed 4. On the inner ends of the armature shafts 6 is a pair of co-operating grinding plates 8 55 mounted in a case 9 on the bed 4. Mounted

on the case 9 is an upstanding feed spout 10 arranged to discharge into the eye of one of the grinding plates 8 and has on its upper end a hopper 11 for holding stock to be delivered to the grinding plates 8. The parts thus far described are of standard and well known construction.

Referring now in detail to the invention, the numerals 12 and 13 indicate a pair of 60 co-operating feed rolls journaled in the bottom of the hopper 11, the former of which has a smooth periphery and the latter of which has a corrugated periphery. A pair of hopper plates 14 are secured in the hopper 65 11 above the rolls 12 and 13 for supporting part of the stock in said hopper and directing the same between said rolls. Keyed to the shaft of the roll 13, outward of the hopper 11, is a face friction wheel 15 with which 70 co-operates a peripheral friction wheel 16 having on its hub a shipper collar 17. Said peripheral friction wheel 16 is keyed to a long counter-shaft 18 journaled in bearings 75 19 on the bed 4. The counter-shaft 18 extends parallel to the face friction wheel 15 and supports the peripheral friction wheel 16 for diametrical adjustments on said face 80 friction wheel. The countershaft 18 is driven from one of the armature shafts 6 by 85 a belt 20 which runs over a relatively small pulley 21 on the respective motor shaft and a relatively large pulley 22 on the counter-shaft 18.

To adjust the peripheral friction wheel 16 90 on the face friction wheel 15 for different speeds and for moving the same from one side to the other of the axis of said face friction wheel when the motor 5 driving the counter-shaft 18 is reversed to continue to 95 drive the corrugated roll 13 in the same direction, I provide a hand crank 23 journaled in a bearing 24 on one of the bearings 19 and having keyed thereto a sprocket wheel 25 which meshes with a rack 26 on a rod 27 100 which extends parallel to the counter-shaft 18 and is journaled in bearings 28 on certain of the bearings 19 and has a shipper arm 29 which engages the shipper collar 17.

As previously stated, the motors 5 are operated to reversely rotate the grinding plates 8 until the edges of the ribs of said plates are worn off on one side and then said motors are reversed to reverse the grinding plates 8 so that the other edges of their ribs 110 may be used until worn out. At the time the motor is reversed the operator operates the

crank 23 to move the peripheral friction wheel to the opposite side of the axis of the face friction wheel 15 so that the corrugated roll 13 is operated in the same direction to properly feed stock from the hopper 11 to the grinding plates 8. The smooth roll 12 is driven from the corrugated roll 13 by a pair of gears 30.

From the above description it is evident that the peripheral friction wheel 16 may be adjusted on the face friction wheel 15 so that the feed rolls 12 and 13 are driven at the proper speed to deliver just the right amount of stock to the grinding plates 8.

15 The corrugated roll 13 co-operating with the smooth roll 12 positively feeds the stock in the hopper 11 to the grinding plates 8 so that there is a constant and even flow. By driving the feed rolls 12 and 13 from one of 20 the motors 5 the feeding action of said rolls always has a definite relation to the grinding action of the grinding plates 8.

By moving the peripheral friction wheel 16 out of engagement with the face friction wheel 15, the rotation of the rolls 12 and 13 may be stopped to cut off further flow of the stock to said rolls. This is highly important in case of a shut-down when the hopper 11 is full of stock, to prevent clogging of the mill. Obviously, by moving the peripheral friction wheel 16 out of engagement with the face friction wheel 15 on either side of its axis, the feeding action of the rolls 12 and 13 will be instantly stopped. It will be noted that the peripheral edge portion of the face friction wheel 16 is beveled so that the peripheral friction wheel 15 will easily ride onto the same when setting said peripheral friction wheel 16 in an operative position.

40 What I claim is:

1. The combination with a pair of co-operating members, and power means for op-

erating the same, of a corrugated feed roll for the members, and friction, variable speed, driving connections for the feed roll from the power means.

2. The structure defined in claim 1 in which the power means for the members is reversible, and in which the driving connections for the feed roll is reversible.

3. The combination with a pair of co-operating members, and a reversible motor for operating each member, of a pair of feed rolls for the members, one of which is corrugated, and friction, variable speed, reversible, driving connections for the feed roll from one of the motors.

4. The combination with a pair of co-operating reversely acting members, and a reversible motor for each member, of a feed roll for the members, and friction, variable speed, reversible, driving connections for the feed roll from one of said motors.

5. The combination with a pair of co-operating, reversely acting members, and a reversible motor for each member, of a pair of co-operating feed rolls for the members, one of which is corrugated, and friction, variable speed, reversible driving connections for the corrugated roll from one of the motors.

6. The combination with a pair of co-operating reversely acting members, and a reversible motor for each member, of a pair of co-operating feed rolls for the members, one of which is corrugated, and reversible driving connections for the corrugated roll, from one of the motors, including a face friction wheel on the corrugated roll, a co-operating peripheral friction wheel, and means for moving the peripheral friction wheel diametrically on the face friction wheel.

In testimony whereof I affix my signature.

WEBSTER LOKEN.
